UNITED STATES PATENT OFFICE.

RALPH MORGAN RUSSELL, OF BIRMINGHAM, ALABAMA.

REFLECTOR FOR FOCUSING CATHODE-RAYS.

SPECIFICATION forming part of Letters Patent No. 579,808, dated March 30, 1897.

Application filed September 15, 1896. Serial No. 605,927. (No model.)

To all whom it may concern:

Be it known that I, RALPH MORGAN RUSSELL, a citizen of the United States, and a resident of Birmingham, in the county of Jefferson and State of Alabama, have invented certain new and useful Improvements in Reflectors for Focusing Cathode-Rays; and I do hereby declare that the following is a full, clear, and exact description of the invention, which will enable others skilled in the art to which it appertains to make and use the same, reference being had to the accompanying drawings, which form a part of this specification.

15 My invention relates to an improved reflector for focusing the X or cathode rays from a Crookes tube directly onto a focal body, whereby the image may be projected upon a fluoroscopic screen.

20 As is now known, the cathode-rays of a Crookes tube cannot penetrate a dense substance, such as lead or platinum, and advantage is taken of such fact by locating the tube in a lead-lined box with a front opening, so that the X-rays, instead of being absorbed by the lead, will be reflected onto the focal object in front of a fluoroscopic screen.

I have found by experiment that lead alone will not perfectly reflect the X or cathode rays, for while it possesses sufficient density it should also have a certain degree of springiness or resiliency to cause perfect reflex action, so that the rays will more thoroughly penetrate the focal object.

35 I have found by experiment that by making the reflector of a dense material, such as lead, zinc, platinum, or nickel, concavo-convex in form, and lining it with a dense springy or resilient substance, such as tin, steel, or iron, the X-rays from a Crookes tube located in the reflector are more properly focused on a focal object than when lead or platinum is used alone. I have also found that by lining the focuser or reflector with a

40 pile fabric of a dark color, such as purple, dark blue, or black velvet, the power of the focuser will be increased, as the velvet will absorb other rays in its field, which would

interfere with the X-rays and cause the shadows to be deeper or more pronounced on the 50 fluoroscopic screen.

The invention consists in the novel construction and combination of parts hereinafter fully described and claimed.

In the accompanying drawings, Figure 1 is 55 a side elevation of a focuser or reflector constructed in accordance with my invention. Fig. 2 is a central longitudinal section. Fig. 3 is a front view.

In the said drawings the reference-numeral 60 1 designates the reflector, made of a concavo-convex shell of lead or other similar material, or in the form of a concave semisphere. This lead on its inner side is provided with a shell or a lining 2, of tin or other similar 65 material, which in turn is covered with a pile fabric 3, such as dark velvet. The numeral 4 designates the Crookes tube. At opposite sides of the reflector are pins 5, to which are pivoted legs or supports 6, held in place 70 thereon by screw-knobs 7. These pins form pivots which turn in the legs to allow the reflector to be adjusted. The numeral 8 designates a counterbalance-weight.

The operation will be readily understood 75 from the foregoing.

Having thus fully described my invention, what I claim is—

1. As an improved article a focuser for X or cathode rays, consisting of the outer concavo-convex shell of lead or other inelastic metal, and an inner shell or lining of tin, or other elastic metal, substantially as described.

2. The combination with the focuser consisting of the concavo-convex leaden shell, 85 the inner shell of tin, and the velvet lining, of the Crookes tube located in the concavity of the focuser or reflector; substantially as described.

In testimony that I claim the foregoing as 90 my own I have hereunto affixed my signature in presence of two witnesses.

RALPH MORGAN RUSSELL.
